PAIR OF SUNGLASSES OR THE LIKE

Atherton R. Mitchell, Dillon Beach, Calif., assignor to Sea & Ski Corporation, Millbrae, Calif.

Filed Oct. 11, 1965, Ser. No. 87,393

Term of patent 7 years

(Cl. D57—1)

FIG. 5

FIG. 1 5|

FIG. 4

FIG. 2

FIG. 3

FIG. 1 is a top plan view of my new design thereof.
FIG. 2 is a front elevational view thereof.
FIG. 3 is a side elevational view thereof.
FIG. 4 is a bottom plan view thereof.

FIG. 5 is a sectional view thereof taken on line 5—5 of FIG. 1, the temple end being shown broken away.

It is to be understood that the criss-cross surface ornamentation shown partially in FIG. 2 covers the entire area encompassed thereby. The rear, not shown, is unornamented.

I claim:

The ornamental design for a pair of sunglasses or the like, as shown and described.
